UNITED STATES PATENT OFFICE.

JOSEPH F. ECCLESINE, OF WHITE PLAINS, NEW YORK.

TASSEL END FOR STRANDS.

Application filed May 22, 1926. Serial No. 110,982.

This invention relates to a tassel or fringed end for a strand or lacing member, and particularly to a method and means for confining the end for threading purposes, 5 threading an ornament upon the body of the strand, and retaining such ornament thereon.

In fringed lacings or tassel ends it has been found necessary to confine the free ends 10 of the material to permit threading through eyelets in the various applications such as for lacing purposes, and the confining tips must be subsequently removed to permit spreading of the fringed ends by which the 15 desired ornamental effect is obtained. It is desirable, however, to provide such ends with further ornamentation in the form of a mold or bead threaded upon the lacing and suitably retained thereon, for instance by a 20 binding or knot at the connected end of the fringe, which mold forms a convenient means for manipulating the ends of the strand and may also be used to conceal such binding or knot.

25 The invention has for an object to provide a novel construction of tassel end for a strand in which the fringed portion is temporarily confined to permit the threading thereover of an ornamental device which 30 may be retained upon the strand against removal by suitable means.

A further object of the invention is to provide a strand having a fringed end and a binding or knotted portion at the inner 35 end of the fringe portion in connection with a finishing member slidingly mounted upon the strand and retained by said binding against withdrawal therefrom.

Another object of the invention is to provide 40 a new method of forming a tassel end for a strand consisting in confining the free threads of said end by a separable tip, threading upon the strand an ornamental device, and forming a binding at the connected end of the tassel of sufficient diameter 45 to retain said device upon the strand.

Other and further objects and advantages of the invention will be hereinafter set forth and the novel features thereof defined 50 by the appended claims.

In the drawing:-

Figure 1 is a perspective showing one application of the invention;

Figure 2 is an elevation of the device with 55 one end completed;

Figure 3 is a similar view with parts in section, showing a further step in the method of production;

Figure 4 is a like view at the final step of 60 production; and

Figure 5 is an elevation with parts in section, showing another means for temporarily confining the tassel end.

Like reference numerals designate corresponding parts throughout the several figures of the drawing.

While the invention has been shown in Figure 1 as applied to a shoe lacing, it is not confined to such application and may be used for other lacing purposes upon garments or otherwise, and also for ornamental effects other than lacings. It therefore comprises a body or strand 10 of any suitable material or length, the free ends of which are formed with fringed portions 11 to provide a tassel end for the device. This strand may be composed of any preferred material or produced in various manners, the form shown being a tubular braided fabric in which the thread ends are 70 extended to form the fringe.

In order to permit the threading of an ornamental device upon the strand or the threading of the strand through suitable lacings, the free ends of the fringed portion 11 may be confined by any suitable tip 75 separably applied, such as shown at 12 in Figure 2. In this form of tip it is clamped to the ends of the fringe and such ends bodily removed with the tip by severing on the line 13, as indicated in Figure 3. Such a free end, however, is without ornamentation and rather unsightly in appearance because there is no proper binding at the 80 connected ends of the fringe nor finishing device at that point. To remedy this objection I thread upon the strand a mold or bead such as indicated at 14, which may be formed of wood or any other desired 85 molded product and is preferably provided with an ornamental covering, as at 15, and a central aperture 16 of substantially the diameter of the strand.

After the application of this mold the inner end of the threaded portion is bound or retained against further raveling by a suitable binding such as a knot 17 which is of a diameter greater than that of the aperture 16 of the mold and prevents the removal of the latter from the strand. It 105

may also be desirable to conceal this knot or binding to increase the attractive effect of the end, and for that purpose the aperture 16 may be enlarged at one or both ends of the mold to embrace the knot 17, as indicated in Figure 4. It is not essential, however, that this mold or bead be disposed at the binding portion as it may be otherwise located upon the strand as indicated at the right of Figure 5.

A modified form of the confining tip is indicated in Figure 5 where it comprises a slideable clip 18 mounted upon the fringed end 11 of the strand 10 and adapted to be slidably removed therefrom after the threading either through the mold or eyelets is completed.

From the foregoing description it will be seen that this invention presents a novel form of ornament for a tassel end which is adapted to cooperate with the binding for the fringed portion of such end which prevents its withdrawal from the strand, and the invention also presents a novel method of forming such a tassel end by which the mold is threaded upon the strand, the threaded portion knotted at its inner end, and the threading tip removed from the threaded portion. The invention is adapted to a wide field of application and is not confined to a lacing strand as the ornamented tassel end is adapted for many other purposes. The specific means for confining the fringed end of the strand and for binding the same may be varied as well as the character of the mold threaded thereon, without departing from the spirit of the invention as defined by the appended claims.

Having thus described my invention,

what I claim as new and desire to secure by Letters Patent of the United States is:—

1. A strand having a fringed end and a binding at the inner end of the fringed portion, a finishing mold slidably mounted upon the strand and retained thereon by said binding, and removable confining means embracing the fringed end to permit threading thereof.

2. A strand having a fringed end and a binding at the inner end of the fringed portion, a finishing mold slidably mounted upon the strand and retained thereon by said binding, and a confining tip embracing the free end of the fringed portion and adapted to be removed therefrom.

3. A tassel end for a strand comprising a fringed portion knotted at its connection with the strand, and a finishing mold slidably mounted upon the strand and adapted to embrace and conceal said knot.

4. The method of forming a tassel end for a strand consisting in confining the free threads of said end by a separable tip, threading upon the strand an ornamental device, and forming a binding at the connecting end of the tassel of sufficient diameter to retain the device upon the strand.

5. The method of forming a tassel end for a strand consisting in confining the free threads of said end by a separable tip, threading upon the strand an ornamental device, forming a binding at the connecting end of the tassel of sufficient diameter to retain the device upon the strand, and removing the tip to free the confined threads.

In testimony whereof I affix my signature.

JOSEPH F. ECCLESINE.
